FRANK A. GAUGER AND ROY W. JOHNSON, OF MILWAUKEE, WISCONSIN, ASSIGNEES,
BY MESNE ASSIGNMENTS, TO TIME-O-STAT CORPORATION, OF MILWAUKEE, WIS-
CONSIN.

FLUID-ACTUATED CONTROL DEVICE.

Application filed February 14, 1921. Serial No. 444,944.

To all whom it may concern:

Be it known that we, FRANK A. GAUGER and ROY W. JOHNSON, both citizens of the United States and residents of Milwaukee, in the county of Milwaukee and State of Wisconsin, have invented new and useful Improvements in Fluid-Actuated Control Devices; and we do hereby declare that the following is a full, clear, and exact description thereof.

This invention relates to certain new and useful improvements in fluid actuated devices and refers more particularly to such a device capable of a diversity of uses.

15 The present automatic type of household water heating device, in which a valve is operated upon the opening of the hot water faucet to light the heater burner, is subject to many objections, one of which is its 20 expensiveness of operation due to the tremendous flame that is necessary in order to insure the proper heating of the water as it is drawn through the heater. Furthermore this type of device does not permit the heating 25 of a full tank of water as the water is heated only as it is drawn through the heater coils.

Hence with the above and other objections 30 to the existing types of automatic water heating devices in mind, this invention has for one of its objects to provide means operable by the full opening of the water faucet to light the heater burner without withdrawing the water from the supply tank 35 and operable upon a partial opening of the faucet to extinguish the burner and permit the withdrawing of the water.

It is another object of this invention to 40 provide a fluid control device in which a casing is utilized having an inlet and an outlet, the inlet of which is connected with a source of fluid supply and which is controlled by a valve member, said valve member being operated automatically upon the 45 fluid entering the inlet reaching a predetermined rate of flow to close the outlet from the casing.

A further object of this invention is to 50 provide a fluid actuated device of the class described, the principle of which is equally applicable for use in connection with air compressors as well as in connection with water heating devices or the like.

55 A still further object of this invention is to provide a device of the class described

which is capable of ready attachment to water heaters or air compressors that are now in use without the necessity of expensive additional fixtures or parts or which may be applied thereto at the time of their manufacture without appreciably increasing the cost thereof.

With the above and other objects in view which will appear as the description proceeds, our invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, we have illustrated two complete examples of the physical embodiment of our invention constructed according to the best modes we have so far devised for the practical applications of the principles thereof, and in which:

Figure 1 is an elevational view of a water heating system equipped with our improved fluid actuated burner controlling device;

Figure 2 is a view part in section and part in elevation taken longitudinally through the fluid actuated device and the valve member positioned within the burner fuel supply line;

Figure 3 is a view illustrating the manner of connecting the fluid actuated device with the fuel control valve, said view being taken on the line 3—3 of Figure 2;

Figure 4 is a view in elevation of a pressure tank and a compressor for supplying air to said tank and illustrating another use of our improved fluid actuated device, and

Figure 5 is a view part in section and part in elevation taken longitudinally through that form of our invention depicted in Figure 4.

Referring now more particularly to Figures 1 to 3 inclusive, 6 designates a water tank of any well known construction and having a water supply pipe 7 connected therewith and an outlet pipe 8 leading therefrom at some point near the top thereof for supplying the water in said tank to a faucet 9. The water in the tank 6 is adapted to be heated by a device 10 which is of the usual construction consisting of an outer casing in which is enclosed a water

coil 11 having its lower end connected with the lower portion of tank 6 by a pipe 12 and its upper end connected with the top of the tank by a pipe 13, said coil being in the 5 path of the flames from a burner 14.

The burner 14 is connected with a source of fuel supply by a pipe line 15 and said pipe line has a control valve 16 positioned therein and adapted to be operated by 16 means actuated by the flow of fluid through the pipe line 8 and now about to be described. Said valve 16 consists of a casing having an inlet and outlet divided by an intermediate partition 17 in which is positioned a passage way 18, said passage way being normally closed by a valve construction 19. The valve construction 19 consists of a nipple 20 removably secured in a bored boss 21 and having its inner end in tight 20 engagement with the port 18 and provided with a central partition 22 through which passes the stem 23 of a valve member 24 seating on the inner end of said nipple as best shown in Figure 2. The valve member 25 24 is normally held in engagement with its seat by an expansile spring 25 coiled about that portion of the valve stem confined within the bore of the nipple outwardly of the partition 22, and having its ends abutting 30 said partition and a removable cap or plug 26 threaded on the outer end of the valve stem. The plug 26 is movable into the bore of the nipple to overcome spring 25 and unseat valve 24 to permit the flow of 35 fuel to the burner 14. In order to insure the lighting of the burner 14 upon the unseating of the valve 24, a pilot 27 is provided which obtains its fuel through an opening 28 communicating with the interior 40 of the valve 16 on the side of the partition 17 connected with the supply side of the pipe line 15.

The pipe line 8 leading from the tank 6 to the faucet 9 is medially disconnected and 45 has the end 28 thereof connected with the inlet 29 of a casing 30 and the end 31 thereof connected with the outlet 32 of said casing. Said casing is provided with a partition 33 between its inlet and outlet which is centrally bored as at 34 to provide a communicating port in substantial axial alignment 50 with the axis of the valve stem 23 through which passes the rod or stem 35 of a plunger 36 slidably mounted in that portion of the 55 casing with which the end 28 of that part of line 8 leading directly from the tank 6 is connected.

The rod or stem 35 passes outwardly 60 through an opening in the wall 36 of the casing nearest the valve 16 and has its extreme outer end positioned adjacent the cap 26 carried by the valve stem 23. The casing 30 is provided with a stuffing box or gland 37 at the point where the stem 35 passes outwardly thereof in order to prevent the leak- 65

age of the fluid within the casing about said stem. With this construction it will be obvious that a movement of the plunger 36 from right to left, with reference to Figure 2 will cause the stem 35 to engage the cap 70 26 and move the stem inwardly against the action of its spring 25 to unseat valve 24 and permit the flow of fuel to the burner 14, and such movement of the plunger is yieldingly resisted by a spring 38 coiled 75 about stem 35 and confined between the casing wall 36 and the valve head portion or boss 39 of the plunger.

The inlet 29 has a partition 40 dividing the same from that portion of the casing in 80 which the plunger is mounted and said partition has a large and a small port 41 and 42 respectively, the port 41 communicating with the side of the plunger nearest the partition 33 and the port 42 communicating with the other side of said plunger when the same is in its position freeing the port 34 to permit the flow of fluid through the casing from the pipe section 28 to the pipe section 31. The port 41 is of such an area that when the faucet 9 is fully opened the flow of fluid into the casing will be of such a pressure as to more than fill said port area as a result of which the pressure 90 acting on the rear of the plunger 36, by reason of the port 42 communicating therewith, will become greater than the force of spring 38 and move the plunger toward the left with reference to Figure 2. As the plunger moves to the left the area of port 41 decreases and the pressure thus exerted on the outer face of the plunger 36 becomes greater to supply the force necessary to overcome the increased tension of the spring 38 as the same is compressed. The plunger 36 moves 95 against the action of the spring 38 until its valve part 39 completely closes the port 34 and prevents the flow of fluid from one part of pipe 8 to the other and at the same time 100 opens the valve 24 in the manner hereinbefore described to light the burner 14. 105

As long as the faucet 9 is left fully open the plunger 36 will be retained in its position holding the valve 24 open and disconnecting the sections of the pipe 8 and when the operator is of the opinion that the water is sufficiently hot the faucet 9 is closed as the result of which the spring 38 will force the plunger 36 to its normal position, the fluid between the plunger and the end wall 43 of the casing being permitted to pass through a minute equalizing hole 44 in the plunger 36 when the valve 24 will also be closed by its spring 25. The operator may then open the faucet 9 to any point up to that where the volume of water passing through the pipe 8 is not greater than the area of port 41. 115

The device is adjustable as the wall 43 is in the form of a threaded plug adjustably 120 125

secured in the outer end of the casing 30 and is further adjusted by a threaded stem 45 carried by said cap with its inner end abutting the plunger 36 when in its normal position and its outer end exteriorly of the casing and provided with a knurled head 46. A stuffing box or gland 47 is provided to prevent the leakage of fluid from the casing about the stem 45.

16 The valve member 16 and casing 30 are readily detachably secured together in their proper position of alignment by a bracket member 48 having one end secured as at 49 to the casing 30 and its other end struck upwardly as at 50 and bored to receive the boss 21 of the valve 16, said upstanding part 50 being detachably secured to said valve boss by suitable fastening means 51. The casing 30 is also provided with an opening 29 which is normally closed by a removable drain plug 52 in order to permit the draining of said casing without disconnecting the pipe line 8.

25 In Figures 4 and 5 our improved fluid actuated device is illustrated as in use in connection with a compressor 53 and is positioned within the pipe line 54 which leads from the compressor to a storage tank 55. The present method of connecting a compressor with a storage tank is objectionable as the compressor is forced to overcome, beginning with its very first stroke, the full pressure within the tank 55, as a result of which a very powerful drive motor (not shown) is necessitated. By positioning our device within the line 54 intermediate the compressor 53 and a check valve 56, the need of an extra large drive means is eliminated as the first power strokes of the compressor 40 are forced to overcome nothing more than atmospheric pressure and do not supply the tank 55 until the operation of the compressor is sufficient to overcome the pressure within the tank. That form of our invention depicted in Figures 4 and 5 is operated on the same identical principle as hereinbefore described and the only material structural change is the provision of an additional outlet 57, the other outlet 32 being 50 discharged into the atmosphere.

55 When the compressor 53 is started, the fluid compressed within its cylinder will pass into the casing 30 through the inlet, and by reason of the check valve 56 being held closed by the pressure within the tank 55, the fluid will take the course of least resistance and flow through port 34 and into the atmosphere through the outlet 32. When the compressor 53 is working at sufficient speed to produce fluid the pressure of which is too great for the area of port 41, which pressure is preferably equal to or slightly less than that within tank 55, the pressure between plunger 36 and wall 43 60 overcomes the spring 38 and moves the

plunger upwardly until the valve part 39 seats with the port 34 to close the same when the inlet 41 and outlet 57 will be in direct communication, as the result of which the fluid will flow through line 54 into the storage tank 55.

We claim:

1. A device of the character described, comprising a casing having an inlet and an outlet, means connecting the inlet with a source of fluid, a plunger member mounted in the casing for movement to and from a position disconnecting the inlet and outlet, mechanical means normally urging the plunger member to a position with the inlet and outlet connected, and a plurality of ports interposed between the inlet and the interior of the casing, one of the ports communicating with the casing on the side of the plunger nearest the outlet and another of the ports communicating with the other side of the plunger, whereby an increase in the rate of flow of fluid beyond the capacity of the first port causes the excess fluid to exert a pressure against the other side of the plunger and move the same against the mechanical urging means to close the outlet. 90

2. A device of the character described, comprising a casing having an inlet and an outlet, means connecting the inlet with a source of fluid, a plunger member mounted in the casing for movement to and from a position disconnecting the inlet and outlet, means normally urging the plunger member to a position with the inlet and outlet connected, a plurality of ports interposed between the inlet and the interior of the casing, one of the ports communicating with the interior of the casing on the side of the plunger nearest the outlet and another of the ports communicating with the other side of the plunger, whereby an increase in the rate of flow of fluid through the casing beyond the capacity of the first port causes the excess fluid to exert a pressure against the other side of the plunger and move the same against the urging means to close the outlet, and equalizing means permitting the return of said plunger member to its position clearing the outlet upon a decrease in the rate of flow of fluid through the inlet. 110

3. A device of the character described, comprising a casing, a partition wall dividing the interior of the casing into an inlet and an outlet chamber, an inlet communicating with the inlet chamber, an outlet communicating with the outlet chamber, a port in the partition wall connecting the inlet and outlet chambers, a plunger reciprocally mounted in the inlet chamber, a valve head carried by the plunger and engageable with the port to disconnect the chambers upon movement of the plunger toward the port wall, a plunger rod fixed to the plunger and passed through the port and through the 130

- end wall of the casing at the outlet chamber, spring means normally urging the plunger and the valve head carried thereby free of the port to permit unrestricted flow between the inlet and outlet, a wall separating the inlet from the inlet chamber and provided with a large and a small opening, the small opening communicating with the inlet chamber between said plunger and the outer wall thereof and the larger opening communicating with the inlet chamber between the plunger and the outlet whereby fluid may be withdrawn from the outlet up to a rate of flow equivalent to the capacity of the larger opening and an increase in the rate of withdrawal from said outlet beyond

the capacity of said larger opening causes the excess pressure to impinge against the outer side of the plunger and move the same to its position with the valve head closing the port, and a passage through the piston to permit the free return of the piston to its normal position upon the rate of withdrawal from said outlet dropping to a predetermined degree. 25

In testimony that we claim the foregoing we have hereunto set our hands at Milwaukee, in the county of Milwaukee and State of Wisconsin.

FRANK A. GAUGER.
ROY W. JOHNSON.
